US0D1053153S

(12) **United States Design Patent** (10) **Patent No.:** **US D1,053,153 S**
(45) **Date of Patent:** **** Dec. 3, 2024**

(54) **SWITCHING DEVICE**

(71) Applicant: **Schneider Electric USA, Inc.**,
Andover, MA (US)

(72) Inventors: **Tannan Whidden Winter**, Fitchburg,
MA (US); **Yee Hsien Tan**, Grenoble
(FR)

(73) Assignee: **Schneider Electric USA, Inc.**, Boston,
MA (US)

(**) Term: **15 Years**

(21) Appl. No.: **29/898,682**

(22) Filed: **Jul. 31, 2023**

(57) **CLAIM**

The ornamental design for a switching device, as shown and described.

DESCRIPTION

FIG. 1 is a front perspective view of a switching device;
FIG. 2 is a front view of a switching device;
FIG. 3 is a back view of a switching device;
FIG. 4 is a left view of a switching device;
FIG. 5 is a right view of a switching device;
FIG. 6 is a top view of a switching device;
FIG. 7 is a bottom view of a switching device; and,
FIG. 8 is another front view of a switching device with a
handle area omitted.

The broken lines in the drawings illustrate portions of a
switching device that form no part of the claimed design.

1 Claim, 8 Drawing Sheets
